UNITED STATES PATENT OFFICE.

EDWIN H. STRONG, OF NEW YORK, N. Y.

NECKTIE-STRETCHER.

1,393,848.

Specification of Letters Patent. Patented Oct. 18, 1921.

Application filed October 1, 1920. Serial No. 414,014.

To all whom it may concern:

Be it known that I, EDWIN H. STRONG, a citizen of the United States, residing at New York, in the county of New York and State of New York, have invented certain new and useful Improvements in Necktie-Stretchers, of which the following is a specification.

The present invention relates to devices for stretching neckties or cravats and consists in the combinations and arrangements of elements hereinafter described and particularly set forth in the accompanying claims.

The invention has for its purpose to provide a device of this character which may be conveniently applied to a cravat or necktie of any size or style for the purpose of keeping the same with the lining thereof in substantially its original form to the end of avoiding the necessity for discarding a tie after the same has been worn but a few times, which condition now prevails.

A further purpose of the invention resides in that the tie form or stretcher does not require the use of a heating iron which "kills" the fabric and is otherwise objectionable; and one wherein the device *per se* serves as a suitable supporting device for the tie when in operative position.

The invention is disclosed by way of illustration in the accompanying drawings wherein Figure 1 illustrates the application of the device to a tie; Fig. 2 is an elevational view of the device *per se*; Fig. 3 is a similar view taken from the opposite side thereof; and Fig. 4 is a transverse sectional view taken on the line 4-4 of Fig. 2.

Referring to the construction in further detail and wherein like reference characters designate corresponding parts in the different views shown, 5 represents an ordinary four-in-hand tie or cravat having the usual lining 6, which may be of any ordinary size or style and to be stretched or kept in substantially its original or new form.

The device consists of a main body portion 7 having converging side edges 8, to which is adjustably attached the two side members 9, whose respective outer edges 10 are also converged after the manner shown.

The adjustable connections between said main and side portions 7 and 9 consist of a plurality of hollow rivets, or pins, 11, that are secured to the side members 9 and work within slots 12 formed in the body

portion 7. The several slots 12 which are disposed in parallel relation to the end that the side members 9 may be moved laterally in uniform manner. A metal piece 13 is secured to the lower edge of the metal portion 7 by the rivets 14 and has an upturned portion 15 providing a groove or channel-way that receives the lower edge portions 16 of the two side members 9 as shown.

The side members 9 are normally distended by means of two springs 17 and 18 located respectively at the ends of the device and on opposite sides thereof. The spring 17 is of the double-bow type and is secured to the middle section 7 as at 19, while the single-bow spring 18 is secured to only the side members as at 20.

A spring clip 21 is secured to a member 7 by a suitable clamping member 22 and has for its purpose to engage the lining 6 of the tie and receive the folds of the tie proper in the way indicated in Fig. 1.

The device may, of course, be constructed of any suitable material such as fiber suitably treated, or metal (e. g. tin) having an enameled finish and it is essential only that the material be of the requisite strength commensurate with appropriate thickness.

In the use of the article the steps to be followed are substantially the following: Lay the wrinkled tie or cravat on a flat surface with the back thereof up and then insert the device with the clip side up. (See Fig. 1.) Smooth the tie on to the form evenly and then pull the lining down and slip it under the lower part of the clip and then pull down tightly to remove any wrinkles. The inner side edges of the tie are now to be inserted within the clip and again pulled down tightly to remove the wrinkles. The tie may be very slightly dampened at the front and back and the holder hung up until the tie is sufficiently dried when it will be found that the same is quite free of wrinkles and closely resembles its original appearance.

Having thus described my invention what I claim as new is:

1. A neck-tie stretcher comprising a flat body portion, and a pair of flat side portions adjustably mounted to overlap said flat body portion, substantially as set forth.

2. A neck-tie stretcher comprising a flat supporting body portion having converging edges, and a pair of flat side portions adjustably mounted on said body portion, said

- side portions having their respective outer edges converging, substantially as set forth.
3. A neck-tie stretcher comprising a flat body portion having converging side edges, 5 a pair of flat side portions having converging outer edges adjustably mounted on said flat body portion, and resilient connection between said side portions normally acting to distend the same, substantially as set forth.
- 10 4. A neck-tie stretcher comprising a flat body portion having converging side edges, a pair of flat side portions having converging outer edges, adjustable pin and slot 15 connections between said body and side portions, and spring members normally acting to distend said side portions, substantially as set forth.
5. A neck-tie stretcher comprising a flat body portion having converging side edges, 20 a pair of flat side portions having converging outer edges, adjustable connections be-
- tween said body and side portions, spring members normally acting to distend said side portions, and a clip mounted on the 25 body portion adapted for holding the lining of the tie while stretching, substantially as set forth.
6. A neck-tie stretcher comprising relatively movable flat and overlapping portions 30 constructed to engage between the folds of the tie, and a device mounted thereon adapted to receive and hold flat the lining of the tie, substantially as set forth.
7. A neck-tie stretcher comprising relatively movable flat and overlapping portions 35 having converging side edges adapted to be placed between the folds of the tie, and a clip mounted thereon adapted to receive and hold flat the lining of the tie, 40 substantially as set forth.

In testimony whereof I affix my signature.

EDWIN H. STRONG.
